ERNEST H. BENNETT, OF EAST ORANGE, NEW JERSEY, ASSIGNOR TO
JOHN H. BROMLEY AND EDWARD BROMLEY, OF PHILADELPHIA, PENNSYLVANIA.

DESIGN FOR A RUG.

SPECIFICATION forming part of Design No. 27,001, dated April 27, 1897.

Application filed March 23, 1897. Serial No. 628,919. Term of patent 7 years.

To all whom it may concern:

- Be it known that I, ERNEST H. BENNETT, a citizen of the United States, residing at East Orange, New Jersey, have invented and produced a certain new and original Design for Rugs, of which the following is a full, clear, and exact description, reference being had to the accompanying drawing, forming a part of this specification.
- 10 My invention relates to the surface ornamentation of a woven rug; and it consists of the design therefor shown in the aforesaid drawing, the distinguishing features being a narrow rectangular border A of small shell-like figures, surrounding an inner border B of somewhat similar figures, the plain field-center being dotted with a series of small irregular leaf figures C and a central medallion figure D.

I claim as new and of my invention—
20 The design for a rug, substantially as set forth.

In testimony whereof I have hereunto affixed my signature this 26th day of February, A. D. 1897.

ERNEST H. BENNETT.
